DESIGN.

—o—

J. A. ORR.

HEATING STOVE.

No. 18,990.

Patented Apr. 2, 1889.

UNITED STATES PATENT OFFICE.

JAMES ALLISON ORR, OF READING, PENNSYLVANIA, ASSIGNOR TO THE
MOUNT PENN STOVE WORKS, OF SAME PLACE.

DESIGN FOR A HEATING-STOVE.

SPECIFICATION forming part of Design No. 18,990, dated April 2, 1889.

Application filed November 7, 1888. Serial No. 290,243. Term of patent 14 years.

To all whom it may concern:

Be it known that I, JAMES ALLISON ORR, a citizen of the United States, residing at Reading, in the county of Berks and State of Pennsylvania, have invented and produced a new and original Design for a Heating-Stove; and I do declare the following to be a full, clear, and exact description of the same, reference being had to the accompanying engravings, forming a part thereof.

My design consists, mainly, in the conformation of the stove, as represented in perspective in the photographs.

The vertical frame A stands at right angles to the square base-plate D, and is provided with a spherical hood, F, with semicircular base 4. The front portion of the cylindrical body of the stove projects through the square opening of the frame A, forming a semi-cylindrical bulged front substantially corresponding in outline with the semicircular base 4. It is provided with curved doors B, which are placed between the base 4 and the curved plate G of the stove-front, and which slide to the rear of the frame A when opened. Curved grate-windows C, bulged beyond the sliding doors, are immediately below the plate G. The ash-pit door E projects still farther from the semi-cylindrical front of the stove, and, inclining forward, covers the greater part of the base-plate D. The cover H has a broad straight front overhanging the frame A, is semicircular in the rear, and has a central pyramidal cap-piece, 1, with convex steps, and is topped with an ornament, 2. The uprights of the frame A are provided with scroll-work panels 5 and 6. The edge 7 of the square base-plate is beveled and ornamented, and the hood F, cover A, doors B and E, and windows C, forming the front and top of the stove, are ornamented, as shown, while all to the rear of the frame A and under the cover H is unornamented.

What I claim is—

1. The design for an open-front stove herein shown and described, comprising the open vertical frame A, with side panels, 5 6, and ornamented spherical hood F, with semicircular band 4, the square base-plate D, with ornamented beveled edge 7, the overhanging cover H, with pyramidal cap-piece 1, having convex steps and top ornament, the cylindrical stove-body projecting through said open frame and forming a semi-cylindrical bulging front with central ornamented band, G, sliding doors B above said band, grate-windows C below it, and the inclined projecting ash-pit door E, extending to near the beveled edge 7 of the base-plate, substantially as set forth. 45

2. In a design for a heating-stove, the overhanging cover H, with broad straight front and semicircular rear outline, ornamented pyramidal edge 8, and central pyramidal cap-piece, 1, with convex steps and top ornament, substantially as set forth. 60

3. In a design for a heating-stove, the open frame A, having uprights with ornamented panels 5 6, ornamented spherical hood F, with semicircular ornamented band 4, and square base-plate D, with beveled ornamented edge 7, substantially as set forth. 65

4. In a design for a heating-stove, the cylindrical body with semicircular ornamented band G, semicircular sliding doors B, semicircular bulged windows C, and projecting inclined ash-pit door E, substantially as set forth. 75

In testimony whereof I affix my signature in presence of two witnesses.

JAMES ALLISON ORR.

Witnesses:

GEO. D. STITZEL,
F. PIERCE HUMMEL.
